UNITED STATES PATENT OFFICE.

SIGMUND SCHIFF, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,104,278.

Specification of Letters Patent. Patented July 21, 1914.

Application filed November 4, 1910. Serial No. 590,635.

To all whom it may concern:

Be it known that I, SIGMUND SCHIFF, a subject of the King of Hungary, residing in the borough of Manhattan, city of New York, in the county of New York and State of New York, have invented certain new and useful Improvements in Type-Writing Machines, of which the following is a specification.

10 The present invention relates to an improved means in a typewriting machine for shifting the platen with respect to the paper guide to permit of correct and easy insertion of considerable thicknesses of paper, 15 or of paper with a clasp and the like attached to it.

Heretofore the platen has been shifted transversely of its shaft and relatively to the paper guide for the above purpose, by 20 means of a special key or finger piece, controlling a number of levers and other parts, and having two functions to perform; to wit, to unlock the platen from the platen shaft, and thereafter to shift the platen 25 with respect to the shaft.

I provide a mechanism in which the system of key controlled levers is eliminated, so that the parts may be few in number, and of simple construction. The mechanism is 30 operated directly by means of a wheel or similar device on the platen shaft; which, in certain forms of the invention, may be one of the hand wheels commonly found at each end of the platen shaft. There is no 35 delay or movement of the parts after the platen is positioned, to unlock the platen, before the shifting of the platen is commenced; the shifting commences without any preliminary unlocking movement. In a 40 form of the invention hereinafter shown the unlocking and shifting movements are resolved into a simple rotation of the platen relatively to the eccentric or other device which is used for shifting the same.

45 I also provide a simple and effective device for preventing shift of the platen except when the same is in such position that the shifting mechanism must operate to throw it in the proper direction.

50 In one form of the invention, a sleeve with eccentrics attached thereto is mounted to turn on the platen axle, the latter journaled in the platen frame and carrying the usual hand wheels for rotating it. The eccentrics are seated in openings formed in

the platen ends eccentrically of the platen to shift the platen transversely of its axis when the eccentrics are rotated relatively to the platen. The platen is normally rotated with the platen axle by means of a disk fixed to the 60 axle and having a slot-and-pin connection with the platen end, the slots being arc-shaped to correspond with the throw of the eccentrics and thereby permit the platen to be shifted transversely of the axle when the 65 eccentrics are rotated in the platen ends, a hand wheel on said sleeve forming a means for rotating the eccentrics. The eccentrics are normally prevented from rotating in the platen and thereby shifting the latter, by 70 means of a pin projecting from the end of the platen into a circular opening formed in a plate on the platen frame, and thereby preventing outward movement of the pin except when the latter is brought opposite 75 a slot forming an extension of the circular opening. In another form of the invention, the eccentrics are rotatable on the platen to shift the latter by means of a hand wheel connected to a sleeve loose on the platen 80 axle and movable endwise on the axle into clutching engagement with the eccentric-carrying sleeve. When the said hand wheel is moved in the opposite direction to release the clutch, it is connected by a bayonet slot 85 and pin to the axle. The sleeve carrying the hand-wheel is prevented from being moved inward to connect said clutch by a plate or collar on the platen frame, except when the sleeve has been rotated to bring a pin or 90 projection thereon opposite a notch in said collar, so that the eccentrics are adjustable to shift the platen only when the platen and axle have been rotated to a predetermined position.

95 Other objects and features of the invention will hereinafter appear.

In the accompanying drawing, Figure 1 is a view in perspective of the platen and of the assembled mechanism for driving and 100 shifting the platen, the parts being shown in normal position. Fig. 2 is a plan, partly cross sectional, of the mechanism shown in Fig. 1. Fig. 3 is a view of the mechanism looking at the left hand end, and showing 105 the means for preventing shift of the platen until the same is turned to proper position. Fig. 4 is a view of the platen and platen shifting mechanism, looking at the right hand end of the platen, the parts being 110

shown in normal position. Fig. 5 is a view similar to Fig. 4 except that the platen is shown in shifted position with respect to the paper guide. Fig. 6 is a plan showing 5 a modified form of mechanism at the right hand end of the platen for shifting and driving the platen. Fig. 7 is a detail view showing certain of the parts of the apparatus shown in Fig. 6.

10 Referring to the form of the invention shown in Figs. 1-5 included, the platen shaft 1 is shown as having attached to the ends thereof the hand wheels 2 and 3. Also fast to the platen shaft is the line-spacing 15 wheel 4 which is engaged in the usual manner by a pawl 5 to effect the line spacing movement of the platen 12. The platen is suitably mounted on the platen frame, a portion of which is shown in dotted lines 20 at 6 in Fig. 2. The end plates 7 and 8 of the platen are shown as fitted upon eccentric disks 9 and 10 by means of which the platen is supported on the platen shaft. The eccentrics 9 and 10 are not, however, 25 fast to the shaft, but are fast to a sleeve 11 within which the shaft is fitted and which is adapted to be rotated relatively to the shaft for shifting the platen, by means of the eccentrics, transversely of the shaft. For 30 convenience in assembling, the sleeve 11 is shown in two parts, one part 11^a of which carries a wheel 13 by means of which the sleeve is rotated relatively to the shaft. The eccentrics are secured to the sleeve by means of 35 set screws 14, and in order that the two sections of the sleeve may turn together, the right hand eccentric is made fast to both sections by means of two set screws. Fast, by means of a set screw 15, to the left hand 40 end of the shaft, against the end plate 7 of the platen, is a plate or disk 16, which engages, by means of slots 17 and 18 in the disk with pins 19 and 20 carried by the end plate 7, in such a manner that when the 45 shaft with the disk 16 is rotated the latter acts upon the pin 19 or the pin 20, (according to the direction of rotation of the shaft), to rotate the platen. The slots 17 and 18 are semi-circular in form to permit of the shift 50 of the platen with the pins 19 and 20, when the eccentrics are turned relatively to the platen by means of the hand wheel 13. The plate 16 and the flanges 21 on the eccentrics prevent longitudinal displacement of the 55 platen.

It is desirable to prevent shift of the platen except when the eccentrics are in one angular position, indicated in any suitable manner as by means of mark 22 on the face 60 of the platen, said position preferably being such that the platen, when shifted, will be carried away from the paper guide. The platen with the eccentrics is therefore turned to bring the mark 22 to said angular 65 position before hand wheel 13 is turned to

shift the platen, which position may be indicated, if desired, by a similar mark on the platen frame with which the mark 22 is aligned. For preventing the shift of the platen at other times, there is attached to the platen frame 6 a plate 23 having a central circular opening 24 through which the platen shaft extends. The pin 20 is not of sufficient length to reach the face of the plate 23, but the pin 19 is extended beyond the face of the disk 16 and enters the opening 24 in the plate 23. The opening 24 is of such diameter that the pin 19 may be turned therein, around the shaft 1 as a pivot, when the disk 16 is revolved with the 70 platen. The periphery of the opening 24, however, closely embraces the path of movement of the pin 19 so as to prevent shifting of the platen except when the angular position of the platen is such that the pin 19 registers with a slot 25 in the plate 23, as shown in Fig. 3. When, by means of the mark 22, pin 19 has been brought to the Fig. 3, position, the platen may be shifted by the eccentrics, and the pin 19, moving with the 80 end plates 7 and 8 of the platen and following its own slot 17, enters the slot 25 in the plate 23.

The normal position of the parts is shown in Fig. 1. The sleeve 11 which carries the 85 eccentrics is not locked to the shaft 1 but snugly engages the same. The end plates 7 of the platen embrace the eccentrics sufficiently closely to prevent play or loose movement between the parts, but not so 90 tightly as to offer appreciable friction to relative rotation of the parts. When the parts are in normal position and the platen shaft is moved by the line spacing wheel or by the hand wheels, the movement of either 95 of these is transmitted to the plate 16. If the movement of the hand wheel 2 is in the direction of the arrow (see Fig. 1), the plate 16, bearing against the pin 19 at the end of the slot 17, carries with it this pin and the 100 platen. If the rotation is in the opposite direction, it is the pin 20 against which the plate 16 bears to rotate the platen. The eccentricity of the eccentrics is not large and there is no leverage exerted by the plate 16 105 which would tend to cause the same to slip on the eccentric and thereby be shifted. The pin 19 furthermore, when bearing against the plate 23, positively prevents the shift of the platen during the normal rotation of the 110 parts. The parts, therefore, move as a unit 115 either backward or forward under normal conditions.

When it is desired to shift the platen, and the parts are in the position shown in Fig. 3 120 so that such shifting is possible, the hand wheel 3 is held against rotation, and the wheel 13 with the sleeve 11 is rotated in the direction of the arrow on the wheel 13 in Fig. 1. The movement of the sleeve 11 is 125

transmitted to the eccentrics, and the plate 16 being held stationary to prevent rotation of the platen, the latter is shifted bodily on the eccentrics from the Fig. 4 position to 5 the Fig. 5 position, so as to move the platen away from the paper guide 26 and feed rolls 27. The pins 19 and 20 are thrown by this movement to the other ends of their slots 17 and 18, and, by engagement with the end 10 walls of these slots, serve as stops to limit the throw of the platen. The paper 28, with clasps 29 or the like, having been inserted and positioned, the platen is returned to 15 normal position by reverse movement of the wheel 13, the hand wheel 3 being held during the return movement by the operator. The return movement to normal position is determined by the pins 19 and 20 engaging the lower ends of the slots.

20 It will be observed that the eccentricity of the eccentric disks 9 and 10 is equal to that of the eccentric openings in the platen ends 7 and 8, so that when the deepest part of the eccentric disk is opposite the narrowest part 25 of the platen ends, the platen axle is concentric with the platen, this position of parts being shown in Fig. 4.

In the form of the invention shown in Fig. 6 the wheel 13 is dispensed with, and the hand wheel 2 is mounted so that it may be disconnected from the platen shaft and connected to the sleeve 11. The platen may then be shifted by holding the hand wheel 3, which remains connected to the platen, 30 and turning the hand wheel 2, which has been connected to the sleeve. In Fig. 6 the plate 16, having its pin and slot engagement with the platen, is, for convenience of illustration, not shown, but these parts are, 35 nevertheless, present, and perform the same functions as heretofore ascribed to them. Instead of the extension 11^a of the sleeve with its wheel 13, the sleeve in Fig. 6 terminates at the eccentric 10, and the latter carries, in addition to the flange 21, one member 40 of a clutch for locking the sleeve and eccentrics to the hand wheel 2 for rotation when the platen is to be shifted. The other member 31 of the clutch, which is normally 45 disengaged from the clutch member 30, is carried by a sleeve 32 to which hand wheel 2 is fixedly attached by means of a set screw 33. The hand wheel 2 is, however normally connected to the shaft 1, so as to rotate the 50 latter, by means of a pin 34 on the shaft, which pin normally engages the sleeve 32. Sleeve 32 has, however, a bayonet joint engagement with the pin 34 on the shaft so that by forcing the hand wheel 2 toward the 55 platen, the sleeve may be moved to bring the clutch member 31 into engagement with the clutch member 30. When the sleeve with the hand wheel 2 has thus been moved, the pin 34 enters that part of the bayonet joint 60 slot 35 which permits the hand wheel 2 to be

turned with the clutch and with the eccentrics, relatively to the shaft 1, to which latter it will be remembered, the hand wheel 3 and plate 16 are fast. This relative turning movement therefore causes the eccentrics to 70 be turned relatively to the platen, and the latter to be shifted as described in connection with Figs. 1 to 5 inclusive. After the turning of the sleeve 32 on the shaft has been commenced, the slot 35 holds the pin 34 75 so that the clutch members cannot disengage, and pressure on the hand wheel 2 is no longer necessary. The relative turning movement of the parts, and the throw of the platen, is determined by the pins 19 and 20 80 engaging the ends of the slots 17 and 18 (see Fig. 5). The pin 34 may however by engagement with the end walls of the slot 35 serve this purpose. When the platen has been returned to normal position so that the pin 34 85 may enter the offset portion of the slot 35, a coil compression spring 40 throws the clutch member 31, and with it the sleeve 32 and hand wheel 2, to normal position and the hand wheel 2 is again locked to rotate with 90 the shaft 1.

A device 23 has hereinbefore been described for preventing shift of the platen except when the eccentrics are in one position, suitably indicated as by a mark 22 on the platen. This same device may be used in connection with shifting mechanism shown in Fig. 6, but in Fig. 6 there is shown another device for the same purpose. This latter device comprises a disk or collar 37 100 attached to the frame member 36 and embracing the clutch member 31. On the member 31 is a pin 39, and at one point of the collar 37 is a notch or opening 38. Unless the platen shaft with the platen and with the 105 clutch member 31 is turned to a position to bring the pin 39 opposite the notch or opening 38, the clutch member 31 cannot be moved into engagement with the clutch member 30, because upon any effort to so move the clutch, the pin 39 will strike the collar plate 37, and the shift of the clutch member thereby be stopped. When however the platen is first rotated to correct position with the pin 39 registering with the opening 38, and the hand wheel is thereafter 110 pressed toward the platen, the pin 39 passes through opening 38, and the clutch members come together, permitting the shift of the platen.

A résumé of the operation of the invention as shown in Fig. 6 is as follows: The platen roll and both the hand wheels and eccentrics being locked to the shaft 1, the same are all turned by either hand wheel until the pin 39 115 lies opposite the opening 38 in the frame-carried plate 37. The handle 3 is then held stationary and the handle 2 is pressed against the action of spring 40, until clutch members 30 and 31 engage. At this time pin 120 125 130

34 is in position to permit of relative rotation of wheel 2 with respect to the shaft and such relative rotation is effected by turning the hand wheel 2 while holding the hand wheel 3. The eccentrics, acting on the end plates 7 and 8 of the platen, shift the platen until pins 19 and 20 engage the upper ends of slots 17 and 18 to stop the shifting movement. The paper being inserted, the movement is reversed until the pins 19 and 20 engage the lower ends of the slots 17 and 18, and the pin 34 is in position to permit the spring 40 to throw back the clutch member 31 with the sleeve 32 and handle 2 to normal position, again locking the handle 2 to the shaft 1, by means of the bayonet joint, and disengaging the handle 2 from the eccentrics.

It will be noted from the foregoing that no key operated lever system is required to effect the unlocking and shifting of the platen with respect to the shaft. It will also be noted that the moment the relative rotation of the parts commences, the shifting of the platen also commences so that there is no preliminary unlocking movement. It will be seen that the platen normally rotates with the shaft. The shaft and the platen, by reason of the eccentrics, are in continuous engagement.

The invention has been shown in two forms only, but it is obvious that all or a number of the features of the invention may be embodied in various other forms within the scope of the invention.

Having thus described my invention, I claim:

1. In a typewriting machine, the combination of a paper guide, a platen frame, a platen shaft supported in the platen frame, a platen, means which connects the platen to the shaft to cause the two to rotate together under normal conditions, the platen being shiftable transversely of the shaft with respect to the paper guide while the platen and shaft are connected by said means, and means on the platen shaft and movable independently thereof for so shifting the platen.

2. In a typewriting machine, the combination of a paper guide, a platen frame, a platen shaft supported in the platen frame, a platen, means forming a positive driving connection between the platen and the shaft to rotate the platen when the shaft is rotated in either direction, the platen being shiftable transversely of the shaft with respect to the paper guide, while the platen and shaft remain connected by said means, and an eccentric rotatable independently of said shaft for shifting the platen.

3. In a typewriting machine, the combination of a paper guide, a platen frame, a platen shaft supported in the platen frame, a platen, means which connects the platen to the shaft to cause the two to rotate to-

gether under normal conditions, the platen being shiftable transversely of the shaft with respect to the paper guide while the platen remains connected by said means to the shaft, an eccentric loose on the platen shaft 70 for shifting the platen, and means for turning the eccentric relatively to the platen shaft.

4. In a typewriting machine, the combination of a paper guide, a platen frame, a platen shaft supported in the platen frame, a platen, means which connects the platen to the shaft to cause the two to rotate together under normal conditions, the platen being shiftable transversely of the shaft 80 with respect to the paper guide while the platen remains connected by said means to the shaft, a sleeve on the shaft, an eccentric fast to the sleeve, and means for turning the sleeve relatively to the shaft to shift the 85 platen.

5. In a typewriting machine, the combination of a paper guide, a platen frame, a platen shaft supported in the platen frame, a platen, means which connects the platen to the shaft to cause the two to rotate together under normal conditions, the platen being shiftable transversely of the shaft 90 with respect to the paper guide while the platen remains connected by said means to the shaft, a sleeve on the shaft, an eccentric fast to the sleeve, and means for turning the sleeve relatively to the shaft to shift the 95 platen.

6. In a typewriting machine, the combination of a paper guide, a platen frame, a platen shaft supported in the platen frame, a platen, a member fast to the platen shaft and having pin-and-slot engagement with the platen to cause the platen and the shaft 100 to rotate together under normal conditions, the platen being shiftable transversely of the shaft with respect to the paper guide, while the said member maintains its engagement with the platen, and means on the 105 platen shaft for so shifting the platen.

7. In a typewriting machine, the combination of a paper guide, a platen frame, a platen shaft supported in the platen frame, a platen, a pin in one end of the platen, a member fast to the platen shaft and having a slot with which said pin engages to cause the platen and the platen shaft to rotate together under normal conditions, the platen being shiftable transversely of the shaft 115 with respect to the paper guide while said pin and slot remain engaged, and means for so shifting the platen.

8. In a typewriting machine, the combination of a paper guide, a platen frame, a platen shaft supported in the platen frame, a platen, a pin in one end of the platen, a member fast to the platen shaft and having a slot with which said pin engages to cause the platen and the platen shaft to rotate to- 125 130

gether under normal conditions, the platen being shiftable transversely of the shaft with respect to the paper guide while said pin and slot remain engaged, and an eccentric disk loose on the shaft for shifting the platen, said slot being semi-circular in shape to permit of the throw of the platen by the eccentric.

9. In a typewriting machine, the combination of a paper guide, a platen frame, a platen shaft supported in the platen frame, a platen, means which connects the platen to the shaft to cause the two to rotate together under normal conditions, the platen being shiftable transversely of the shaft with respect to the paper guide while the platen remains connected to the shaft by said connecting means, means movable independently of the platen shaft for so shifting the platen, and means for preventing shift of the platen except when the parts are in a predetermined angular position.

10. In a typewriting machine, the combination of a paper guide, a platen frame, a platen shaft supported in the platen frame, a platen, means which connects the platen to the shaft to cause the two to rotate together under normal conditions, the platen being shiftable transversely of the shaft with respect to the paper guide, while the platen remains connected to the shaft by said connecting means, an eccentric for shifting the platen, and means for preventing shift of the platen except when the parts are in a predetermined position.

11. In a typewriting machine, the combination of a paper guide, a platen frame, a platen shaft supported in the platen frame, a platen, a pin in one end of the platen, and a member fast to the platen shaft and having a slot with which said pin engages to cause the platen and the platen shaft to rotate together under normal conditions while permitting the platen to be shifted transversely of the shaft with respect to the paper guide without disengagement of said pin from said slot, one of the end walls of said slot, by engagement with the pin, acting as a stop to determine the throw of the platen.

12. In a typewriting machine, the combination of a paper guide, a platen frame, a platen shaft supported in the platen frame, a platen, a member fast to the platen shaft and having a pin-and-slot engagement with the platen on both sides of the platen shaft, to cause the platen and the shaft to rotate together in both directions under normal conditions, the platen being shiftable transversely of the shaft with respect to the paper guide while said member is in engagement with the platen, and means for so shifting the platen.

13. In a typewriting machine, the combination of a paper guide, a platen frame, a platen shaft supported in the platen frame,

a platen, two pins on one end of the platen, one of which pins is on each side of the shaft, an element fast to the platen shaft and having two slots therein, each of which slots is in engagement with one of said pins, and an eccentric for shifting the platen transversely to the shaft, said slots being of a shape to permit of the shift of the platen with pins in the slots, and, when the platen is in normal position, one of said pins, by engagement with an end wall of its slot, acting as a connection to drive the platen from the shaft in one direction, and the other pin similarly acting as a driving connection in the other direction.

14. In a typewriting machine, the combination of a paper guide, a platen frame, a platen shaft supported in the platen frame, a platen, two pins on one end of the platen, one of which pins is on each side of the shaft, an element fast to the platen shaft and having two slots therein, each of which slots is in engagement with one of said pins, and an eccentric disk loose on the shaft for shifting the platen transversely of the shaft, said slots being of a shape to permit of the shift of the platen with pins in the slots, and, when the platen is in normal position, one of said pins, by engagement with an end wall of its slot, acting as a connection to drive the platen from the shaft in one direction, and the other pin similarly acting as a driving connection in the other direction.

15. In a typewriting machine, the combination of a paper guide, a platen frame, a platen shaft supported in the platen frame, a platen, and means for supporting the platen on the platen shaft and rotatable independently of the platen shaft for shifting the platen transversely of the platen shaft, means on the platen shaft co-operating with said shifting means, the bearing surface of the platen on said shifting means being eccentric, so that under normal conditions the shifting means rotates as a unit with the platen by means of said bearing and shifting surface.

16. In a typewriting machine, the combination of a paper guide, a platen frame, a platen shaft supported in the platen frame, a platen, means for supporting the platen on the platen shaft and rotatable independently of the platen for shifting the platen transversely of the platen shaft, means on the platen shaft co-operating with said shifting means, the bearing surface of the platen on said shifting means being eccentric, so that under normal conditions the shifting means rotates as a unit with the platen by means of said bearing and shifting surface, and means for holding the platen against rotation while rotating the shifting means to effect the shift.

17. In a typewriting machine, the combi-

nation of a paper guide, a platen frame, a platen shaft rotatably supported in the platen frame, a platen rotatable with said shaft, means for supporting the platen on the platen shaft and for shifting the platen transversely of the platen shaft, said means rotatable independently of the platen shaft, and a hand wheel on the platen shaft by which said means is operable for shifting the platen transversely of the shaft with respect to the paper guide.

18. In a typewriting machine, the combination of a paper guide, a platen frame, a platen shaft supported in the platen frame and having a hand wheel at each end, an eccentric loose on the shaft, a platen roll supported on the eccentric, means connecting the shaft to the platen roll, and means for disconnecting one of the hand wheels from the shaft and connecting the same to the eccentric so that the hand wheels may be turned relatively to each other to effect the shift of the platen transversely of the shaft.

19. In a typewriting machine, the combination of a paper guide, a platen frame, a platen shaft supported in the platen frame, and having a hand wheel at each end, an eccentric loose on the shaft, a platen roll supported on the eccentric, means connecting the shaft to the platen roll, and a clutch movable longitudinally on the shaft for disconnecting one of the hand wheels from the shaft and connecting the same to the eccentric so that the hand wheels may be turned relatively to each other to effect the shift of the platen transversely of the shaft.

20. In a typewriting machine, the combination of a paper guide, a platen frame, a platen shaft supported in the platen frame and having a hand wheel at each end, an eccentric loose on the platen shaft, a platen roll supported on the eccentric, means connecting the shaft to the platen roll, one of the hand wheels having a bayonet joint connection with the shaft to permit it to be shifted longitudinally on the shaft to a position where it may turn relatively to the shaft, and said shiftable hand wheel carrying a clutch for engaging the eccentric when so shifted longitudinally, whereby the hand wheel thus connected to the eccentric may be turned relatively to the hand wheel connected to the platen to shift the latter transversely of the shaft.

21. In a typewriting machine, the combination of a paper guide, a platen frame, a rotatable platen shaft supported in the platen frame, and means including a part normally rotating with but rotatable independently of the platen shaft, and supported thereon, for shifting the platen transversely of the shaft and with respect to the paper guide.

22. In a typewriting machine, the combination of a paper guide, a platen frame, a

rotatable platen shaft supported in the platen frame, and an eccentric for shifting the platen transversely of the shaft and with respect to the paper guide, the movement of the eccentric relative to the platen and the shifting of the platen commencing simultaneously, the eccentric normally rotating with the shaft and platen but being rotatable independently of the platen shaft.

23. In a typewriting machine, the combination with a platen, of a shaft, means connecting said platen with said shaft to rotate therewith, and a hand wheel on said shaft rotatable relatively to it to shift the platen transversely of the shaft.

24. In a typewriting machine, the combination with a platen, of a shaft, means connecting said platen with said shaft to rotate therewith, a hand wheel on said shaft, means for connecting said wheel to said shaft, means for connecting said wheel to said platen when not connected to said shaft, and a hand wheel permitting an operator to hold said shaft to enable said platen to be shifted transversely of the shaft.

25. In a typewriting machine, the combination with a platen, of a shaft, a hand wheel, means for connecting said hand wheel to said shaft to turn said shaft, means whereby said wheel may be released from said shaft and may be locked to the platen, and means to hold the shaft whereby the platen may be shifted transversely of the shaft.

26. In a typewriting machine, the combination with a shaft, of a platen, a sleeve on the shaft carrying the platen, means connecting said sleeve with the shaft to rotate therewith, and means for rotating said sleeve on said shaft to shift the platen transversely of the shaft.

27. In a typewriting machine, the combination with a shaft, of a sleeve, a platen on the sleeve, a second sleeve on the shaft, a hand wheel on said second sleeve, a connecting device on said second sleeve to connect said second sleeve to said shaft, a second connecting device on said second sleeve to engage with and turn said first sleeve when said first mentioned connecting device is inoperative, means operated by said first sleeve to shift the platen, and means tending to move the parts to cause said first mentioned connecting device to normally connect said hand wheel and shaft.

28. In a typewriting machine, the combination with a platen, of a shaft, a sleeve, a hand wheel on the sleeve to turn said shaft, a clutch having a member connected to said sleeve, and means operated through the clutch to shift the platen with reference to said shaft.

29. In a typewriting machine, the combination with a platen, of a shaft extending

through the platen and normally rotating therewith, and eccentric means movable independently of the shaft but carried thereby and normally rotating therewith, for shifting said platen on and relatively to said shaft.

30. The combination of a platen frame, a platen, a platen shaft normally rotating with the platen, and means between the 10 platen and the platen shaft and normally rotating therewith but movable relatively to both the platen and the shaft, for shifting the platen transversely of the shaft.

31. The combination of a platen frame, a 15 platen, a platen shaft, means between the platen and the platen shaft, and movable relatively to both the platen and the shaft, whereby the platen may be shifted transversely of the shaft, and means for preventing such shifting action except when the 20 parts are in a predetermined rotative position.

32. The combination of a platen frame, a platen, a platen shaft rotatable with the 25 platen, and means between the platen and the platen shaft, and movable relatively to both the platen and the shaft, for shifting the platen transversely of the shaft; said shifting means being pivoted upon the 30 platen shaft and having a rotatable connection with the platen.

33. The combination of a platen frame, a platen, a platen shaft rotatable with the platen, means between the platen and the 35 platen shaft and movable relatively to both the platen and the shaft, for shifting the platen transversely of the shaft, and a finger piece adapted to be connected to said shifting means to operate the same.

40 34. The combination of a platen frame, a platen, a platen shaft, means between the platen and the platen shaft and movable relatively to both the platen and the shaft for shifting the platen transversely of the 45 shaft, a finger wheel normally disconnected from said shifting means but movable into connection therewith, and means for preventing connection being made between the finger wheel and the shifting means unless

the platen is in a predetermined rotative 50 position.

35. The combination of a platen frame, a platen, a platen shaft, means between the platen and the platen shaft and movable relatively to both the platen and the shaft 55 for shifting the platen transversely of the shaft, a finger wheel normally disconnected from said shifting means but movable into connection therewith, and means for preventing connection being made between the 60 finger wheel and the shifting means unless the platen is in a predetermined rotative position; said finger wheel being normally connected to said shaft to rotate the platen.

36. In a typewriting machine, the combination with a platen frame and a platen axle rotatable therein, of eccentrics, a sleeve on the axle carrying the eccentrics and rotatable on the axle, and a platen mounted on the eccentrics, the latter being rotatable in 70 the platen to shift the platen transversely to its axle.

37. The combination with a platen frame and a platen axle rotatably mounted therein, of a sleeve rotatable on the platen axle, 75 eccentrics fixed to said sleeve, and a platen provided with openings to receive said eccentrics.

38. The combination with a platen frame and a platen axle rotatably mounted there- 80 in, of a sleeve rotatable on the platen axle, eccentrics fixed to said sleeve, and a platen having end disks formed with eccentric openings to receive said eccentrics.

39. The combination with a platen frame 85 and a platen axle rotatably mounted there- in, of eccentrics rotatably mounted on said axle, a platen mounted on said eccentrics and normally concentric with the axle, and means to prevent relative rotation of the eccentrics and platen, said means being movable to position to permit such relative rotation and thereby shift the platen.

SIGMUND SCHIFF.
